(57) **CLAIM**

The ornamental design for lighting control switch, as shown and described.

DESCRIPTION

The patent or application file contains at least one drawing executed in color. Copies of this patent or patent application publication with color drawing(s) will be provided by the Office upon request and payment of the necessary fee.

1. Lighting control switch

1.1 : Perspective

1.2 : Front

1.3 : Back

1.4 : Top

1.5 : Bottom

1.6 : Right

1.7 : Left

The elements shown within the yellow highlighted areas form no part of the claimed design.

Reproduction 1.1 is a perspective view; reproduction 1.2 is a front view; reproduction 1.3 is a back view; reproduction 1.4 is a top view; reproduction 1.5 is a bottom view; reproduction 1.6 is a right view; reproduction 1.7 is a left view.
